GAS CONTROLLED AUTOMATIC FIREARM

Charles Sutter, Suresnes, and Eugène Albert Dugied, Courbevoie, France, assignors to Societe Anonyme des Anciens Etablissements Hotchkiss & Cie., Levallois-Perret, France

Application August 8, 1934, Serial No. 739,051
In France April 4, 1934

5 Claims.

(Cl. 42—3)

In the operation of gas controlled automatic firearms, upon firing and after the bullet has passed by an orifice drilled in the barrel at a suitably chosen position, a small fraction of the powder gases passes through said orifice and has ingress into a cylinder located below and parallel to the barrel. With this cylinder there co-operates a movable piston, in parallel relation to the barrel, and which is pushed forward toward the bottom of the cylinder by a return spring. The gases act on this piston and thrust it rearward, thereby compressing the return spring. The piston head then emerges from the cylinder and the gases make their way into the surrounding atmosphere. The kinetic energy, created under the thrust of the gases, is absorbed by the passive resistances and by the compression of the return spring; the piston completes its movement of recoil, the spring as it expands projects it forwardly, whereby another shot is fired, and the firearm caused to operate automatically.

In the known systems, the expansion cylinder is sometimes capped by a sleeve which extends to the rear and surrounds the piston, thus eliminating all danger of the firer being hurt by the piston in its reciprocating movement. Such sleeve has then numerous holes drilled through it to permit of the free exhaust of the gases, as indicated above.

It thus follows from the ordering of gas controlled automatic firearms, that such arms have two orifices for venting the powder gases.

Through the first orifice, constituted by the muzzle of the barrel, the gases are vented to the front of the firearm. Through the second orifice, on the contrary, formed by the rear section of the expansion cylinder, the gases are vented to the rear of the firearm.

This fact has no harmful consequences in the case of firing in the open; such is no longer the case, however, when firing under shelter; while the gases vented through the barrel issue outside the shelter, those vented through the expansion cylinder, on the contrary, flow back towards the inside, thus poisoning the atmosphere in the shelter and rendering it unbreathable.

The present invention has reference to a device by means of which all the powder gases in gas controlled automatic fire-arms are vented to the front of the barrel.

To this end, the expansion cylinder is capped by a sleeve surrounding the piston. Said sleeve thus already acts as a protecting tube for the firer.

Said sleeve includes furthermore longitudinal

ducts formed in the thickness of its shell and over a suitable length thereof forward of the expansion cylinder; said ducts discharge to the front of the barrel and are open at their other end to the interior of the sleeve. They thus form a circuit from rear to front and from the inside of the sleeve to the outside.

It is this circuit that the powder gases follow when the piston head has emerged from the expansion cylinder. The gases are thus compulsorily vented to the front. In its return movement, urged by the return spring, the piston finishes the scavenging of the gases.

No egress of the gases to the rear of the fire-arm has occurred; provided the sleeve used is sufficiently long, the vent ducts will discharge outside the shelter; the air will not be fouled within.

The accompanying drawings illustrate diagrammatically and merely by way of example the application of the invention to two slightly different types of gas controlled automatic firearms.

In these drawings:

Fig. 1 is a longitudinal sectional view of a fire-arm improved in accordance with the invention.

Fig. 2 is the corresponding end view.

Fig. 3 illustrates a different type of firearm, also improved in accordance with the invention.

At the lower portion of the barrel C of the arm 30 illustrated fragmentarily in Figs. 1 and 2, and parallel to said barrel, there is fixed the expansion cylinder D which communicates with the barrel through the duct O. The head of the piston P may engage in this cylinder. About the cylinder 35 is placed a circular sleeve M which extends to the rear, completely surrounding the piston.

A flange E of the piston in contact with the sleeve M prevents the gases from seeping to the rear. In the thickness of the sleeve M are drilled 40 a certain number of longitudinal ducts L which discharge to the outside forwardly and which communicate through a milled cut T with the inside of the sleeve, on a level with the rear portion of the expansion cylinder.

It is thus seen that when the head of the piston P has emerged from the expansion cylinder D (position shown in full lines in Fig. 1) the gases trapped in the sleeve can only make their way out through the longitudinal ducts L, that is to say towards the front end of the fire-arm. When the piston returns forwards, its flange E again forces the residual gases to pass out through the ducts L. The extreme forward position of the 55

piston P is illustrated in dotted lines at P¹ in said Figure 1.

It is of course essential that the point L¹ at which the ducts L discharge shall lie outside the shelter in which it has been assumed that the rear end of the fire-arm is lodged; in the example illustrated, it has been assumed that the shelter is bounded by a partition F illustrated in dotted lines. The point L¹ must therefore lie forward 10 of said partition and to this end the ducts L may be extended by the desired amount when this is necessary.

In these conditions, all the powder gases will be vented outside the shelter within which the 15 atmosphere will not be fouled.

In Fig. 3 the invention has been illustrated as applied to a slightly different type of arm. In this case, the expansion cylinder D is constituted by a bore formed in the piston P which then 20 surrounds a fixed head H. The sleeve M is mounted in the same manner as before and plays exactly the same part.

It will be understood moreover that these two examples of the application of the invention are 25 only given by way of example and that the invention is applicable, in the same conditions and while affording the same advantages, to all types of gas controlled automatic fire-arms.

We claim:

- 30 1. In an automatic gas operated gun, an actuating device including a gas receiving member fixed to the barrel near its outer end having therein a rearwardly directed gas duct communicating with the interior of the barrel, a sleeve fitting tightly about said gas receiving member and extending rearwardly beneath said barrel, a pressure actuated reciprocating member moving in said sleeve and normally engaging with said gas receiving member to close the gas duct 40 therein, said reciprocating member adapted to move under force of gas in said duct to actuate the breech mechanism and open said duct into the sleeve, and a gas exhaust member extending forwardly beneath said gas receiving member and 45 communicating with the interior of said sleeve adjacent the end of the said gas duct to receive and exhaust the operating gases towards the muzzle of the barrel when the reciprocating member moves to open said duct to the sleeve.
- 50 2. In an automatic gas operated gun, an actuating device including a gas receiving member fixed to the barrel near its outer end and having therein a rearwardly directed gas duct communicating with the interior of the barrel, a sleeve fitting tightly about said gas receiving member and extending rearwardly beneath said barrel, a pressure actuated reciprocating member moving in said sleeve and normally engaging with said gas receiving member to close the gas duct 55 therein,

said reciprocating member adapted to move under force of gas in said duct to actuate the breech mechanism and open said duct into the sleeve, and a semi-cylindrical gas exhaust member extending forward beneath said gas receiving member and having exhaust ports therein communicating with the interior of said sleeve adjacent the end of said gas duct to receive and exhaust the operating gases towards the muzzle of the barrel when the reciprocating member moves to open said duct to the sleeve. 5

3. In an automatic gas operated gun, an actuating device including a gas receiving cylinder fixed to the barrel near its muzzle and having a central bore communicating with the barrel and opening toward the breech, a sleeve fitting tightly about said gas receiving member extending rearwardly beneath said barrel, a reciprocable piston movable in said sleeve and normally in the bore of said cylinder closing the same, said piston adapted to move under force of gas in said bore to actuate the breech mechanism of the gun and open said bore into said sleeve, and a gas exhaust member extending forwardly beneath said cylinder and communicating with the interior of said sleeve adjacent the end of said bore to receive and exhaust the operating gases towards the muzzle of the barrel when the piston moves to open the bore to the sleeve. 15 20 25

4. In an automatic gas operated gun, an actuating device including a gas receiving piston fixed to the barrel near its muzzle and having a central bore communicating with the barrel and opening towards the breech, a sleeve fitting about said piston and extending rearwardly beneath 30 said barrel, a reciprocable cylinder movable in said sleeve and having a bore to fit around said fixed piston, said cylinder adapted to move under force of gas in the bore of said piston to actuate the breech mechanism of the gun and open the 35 bore of said piston into said sleeve, and a gas exhaust member extending forwardly beneath said piston and communicating with the interior of said sleeve adjacent the end of the bore in said piston to receive and exhaust the operating 40 45 gases towards the muzzle of the barrel when the cylinder moves to open the bore to the sleeve.

5. In an automatic gas actuated gun having an operating member movable under force of gas tapped from the barrel and an exhaust port for 50 such gas, a gas exhaust member comprising a series of tubes communicating with said exhaust port and extending substantially to the muzzle of the barrel to receive the operating gas under pressure and deliver it at high velocity towards 55 the muzzle of the gun.
